ATTORNEY'S.

UNITED STATES PATENT OFFICE.

JOHN H. ELWARD, OF STILLWATER, MINNESOTA, ASSIGNOR, BY MESNE ASSIGNMENTS, TO E. S. BROWN, RECEIVER, OF SAME PLACE.

SPARK-ARRESTER.

SPECIFICATION forming part of Letters Patent No. 339,538, dated April 6, 1886.

Application filed December 29, 1881. Serial No. 49,005. (No model.)

To all whom it may concern:

Be it known that I, JOHN H. ELWARD, a citizen of the United States of America, residing at Stillwater, in the county of Washington and State of Minnesota, have invented 5 certain new and useful Improvements in Furnaces for Portable Engines; and I do hereby declare the following to be a full, clear, and exact description of the invention, such as will 10 enable others skilled in the art to which it app pertains to make and use the same, reference being had to the accompanying drawing, and to letters or figures of reference marked thereon, which form a part of this specification.

15 The drawing shows in side elevation a traction-engine having my improved spark-arrester applied thereto.

While I have shown my invention applied to a traction or road engine, it will of course 20 be understood that it is equally applicable to engines of other constructions.

In the drawing, A² represents the outer shell 25 of the boiler, within which is situated the fire-flues and furnace. From the flues the products of combustion pass into a rear smoke-chamber, and thence out through the smoke-stack Q, which is made of two parts hinged together, in order that the upper portion may fold down upon the boiler, as is common in 30 this class of engines.

The smoke-stack is provided with a netting, q, above which is placed the spark-arrester Q'. This I have shown in section in order to better illustrate its construction. It is formed 35 with a central conical or semispherical wall, R, provided with a central aperture, r, and with an outer conical or semispherical wall, R'R², extending continuously around and over the top of the wall R, the part R² being hinged 40 at r' in order to permit access to the interior of the spark-arrester.

A water-space is formed between the outer and inner walls, into which the hot and burning sparks and cinders are deflected by means

of a central downward-projecting guide-piece, 45 S¹, preferably carried by the hinged part R² of the spark-arrester, and situated directly over the opening r. Water for quenching such burning sparks and cinders is supplied to the water-receptacle, by a pump or other 50 suitable means, through a pipe, S² S³. The two parts of this pipe are hinged at s' in such manner that the upper part, S³, may be turned down and up with the upper part of the smoke-stack.

55 The smoke and gaseous products of combustion pass out freely into the open air through the netting q, which is of so fine mesh as to prevent the escape of any sparks or cinders of such size as to be dangerous, only the solid heavier particles which pass through the stack entering the spark-arrester Q', which arrangement interferes but little with the draft, the smoke-passage through the stack and into the air being practically straight and unobstructed.

60 What I claim is—

1. In combination with the furnace and the smoke-stack, the netting q, and the spark-arrester Q', above the netting, and provided with 70 a water-receptacle, and also with a deflector adapted to guide the sparks and cinders into said water-receptacle, substantially as set forth.

2. In combination with the furnace and the 75 smoke-stack, hinged to permit the upper section thereof to fold down, the spark-arrester having a water-space, and the water-supply pipe S² S³, arranged in sections and adapted to fold with the smoke-stack, substantially as set 80 forth.

In testimony whereof I affix my signature in presence of two witnesses.

JOHN H. ELWARD.
